DESIGN FOR A LIGHTING FIXTURE

Edward H. Weber, Meriden, Conn., assignor to The Miller Company, Meriden, Conn., a corporation of Connecticut

Application April 11, 1941, Serial No. 100,319

Term of patent 7 years

To all whom it may concern:

Be it known that I, Edward H. Weber, a citizen of the United States of America and a resident of Meriden, in the county of New Haven and State of Connecticut, have invented a new, original, and ornamental Design for a Lighting Fix-ture, of which the following is a specification, reference being had to the accompanying drawing, forming a part thereof.

The single figure of the drawing is a perspective view of the lighting fixture showing my new design.

I claim:

The ornamental design for a lighting fixture,
as shown.

EDWARD H. WEBER.
